[57] CLAIM

The ornamental design for an adjustable pillow, as shown and described.

DESCRIPTION

FIG. 1 is a perspective view of an adjustable pillow showing my new design;

FIG. 2 is a top plan view thereof;

FIG. 3 is a bottom plan view thereof;

FIG. 4 is a side elevational view thereof, the side not shown being a mirror image of the side shown;

FIG. 5 is a front elevational view thereof;

FIG. 6 is a rear elevational view thereof;

FIG. 7 is a top plan view of my new design with the head and appendages retracted to the adjusted position; and

FIG. 8 is a bottom plan view of my new design with the head and appendages retracted to the adjustable position, and with the head opening to the left as viewed.
